D. ATWATER

UNION SUIT

Filed April 25, 1922

FIG. 1.

FIG. 2.

FIG. 3.

David Atwater,
INVENTOR.

BY

Frank A. Cutler,
ATTORNEY.

UNITED STATES PATENT OFFICE.

DAVID ATWATER, OF WESTFIELD, MASSACHUSETTS.

UNION SUIT.

Application filed April 25, 1922. Serial No. 556,492.

To all whom it may concern:

Be it known that I, DAVID ATWATER, a citizen of the United States of America, and a resident of Westfield, in the county of 5 Hampden and State of Massachusetts, have invented a new and useful Union Suit, of which the following is a specification.

My invention relates to improvements in union suits, and consists in combining with 10 such suits permanent hose supporters. The union suits employed are of the full-length type in contradistinction to the knee-length type, and as a rule are of the knitted or woven variety which have seams on the inner 15 sides of the leg portions. The hose supporters are attached to the aforesaid seams or to the seamed parts of the legs of the union suit, below those portions of said legs that cover the knees of the wearer. The hose 20 supporters may be made up in a number of different ways and out of a number of different materials, but usually will consist of clasps or their equivalents and buttons or their equivalents attached to the legs of the 25 union suit, or to the seams or seamed portions thereof as previously stated.

The primary object of my invention is to produce a combination union suit and hose supporters, to the end that the separate and 30 individual or independent hose supporters commonly used shall be dispensed with. It is difficult properly to adjust the ordinary hose supporter to the leg so that it will not bind on the one hand, or be too loose on the 35 other. With the present invention provision is made for supporting the hose without binding the leg or producing any discomfort whatever. In this case the hose are supported or held up in place properly and 40 securely, and the strain is distributed throughout the legs and the other portions of the garment in such a manner as to be unappreciable. Furthermore, these permanently- 45 attached hose supporters eliminate two separate articles of wearing apparel and consequently excel in convenience and as time-savers. Being attached to the seams or seamed parts of the union suit the hose sup-

porters are not liable to tear or unduly strain the fabric of such suit. 50

A further object is to provide a full-length union suit with hose-supporting means which are comparatively simple and inexpensive, and which do not impair in any way the usefulness or ordinary utility of such suit, or seriously interfere with laundering the same. 55

Other objects and advantages will appear in the course of the following description. 60

I attain the objects and secure the advantages of my invention by the means illustrated in the accompanying drawings, in which—

Figure 1 is a perspective view of a union suit which embodies a practical form of my invention; Fig. 2, an enlarged front elevation of a portion of one of the legs of said suit, with one of the hose supporters attached thereto or connected therewith, the same being in side elevation and unfastened or open, and, Fig. 3, an inner side elevation of said leg and of said supporter, the latter being fastened or closed as would be the case if the top portion of a stocking or sock were engaged therewith and held thereby. 65 70 75

Similar reference characters designate similar parts throughout the several views.

An ordinary knitted or woven suit is represented at 1 in Fig. 1, which suit has full-length leg portions 2—2, seamed at 3—3 on the insides from the bottoms thereof to the crotch. The garment supporters are attached to these seams or to the seamed portions of the legs 2 below the parts of said legs that cover the knees of the wearer. 80 85

Each of the aforesaid hose supporters, in the present embodiment of the invention, consists of a clasp 4 connected with one of the legs 2, or with the seam 3 or seamed part thereof, by means of a tab 5, and a button 6 attached also to said leg, or to said seam or said seamed part, below said tab. Each tab 5 is sewed or stitched to the garment, so also is each button 6. 90 95

The clasps 4 are of the usual and well-known type of garment-supporter clasps;

each having a wide opening above and a narrow opening below, so as to enable the clasp to be passed over its associated button 6 and the portion of a hose that is placed over said button, and then drawn upwardly to force said portion of said hose that covers said button tightly into engagement with the latter, all in the usual and customary manner. The top portions of the clasps 4 pass through and are directly supported by the tabs 5, which latter are looped and stitched above said top portions and to the garment at the seams 3.

Each button 6 is located at such a distance below the associated tab 5 as to enable the clasp 4 attached to said tab to engage said button and a hose caught over the same, in the manner required in order to secure and support said hose, without appreciably wrinkling the leg 2 to which the garment-supporting members are attached. In other words, the hose, when held in place by these garment supporters and tending to pull down on the same, cause the seams 3 to be drawn into and maintain approximately straight lines.

In practice, while either clasp 4 is disengaged from the button 6 below, as shown in Fig. 2, the upper portion of a hose is caught over said button, the contiguous portion of the leg 2 to which said button is attached, with the button, and said hose are forced upwardly; or that portion of said leg to which the tab 5 for said clasp is attached is forced downwardly, or both of such portions of said leg are forced toward each other, until said button and the wide portion of said clasp are in adjacent relationship, when said clasp is closed over the hose and button, and the aforesaid portions of said leg are separated, the one from the other or both together, until said button with its covering of hose is crowded or edged into the narrow portion of the clasp. The hose is now held securely by the supporter and prevented from working downwardly on the leg. The strain of the hose is transmitted from the engaging button and clasp to the seamed portion of the garment leg with which they are connected, and thereby distributed to other portions of said leg, and even to the garment above the same. A fragment 7 of a hose is represented as being in the grasp of the hose supporter shown in full lines in Fig. 1.

In releasing or disengaging the hose from either supporter, either of the fabric parts, to which the button and tab are directly attached is forced toward the other, or both of such parts are forced toward each other, until said button and the clasp are in relative position for disengagement, when the clasp is swung outwardly, and the hose is removed from the button.

65 The operations of engaging the hose with

the supporters and disengaging them therefrom are, of course, very similar to those involved in separable and independent or band-hose supporters, except that in the present case the legs of the garment or portions of such legs take the place of elastic elements which constitute parts of said second-named supporters.

As has been previously intimated, considerable latitude must be allowed for the construction or formation of the hose-supporting elements which I may employ, wherefore I do not intend to be restricted to the common clasp and button herein shown and specifically described, but seek 80 to claim broadly any hose-supporting means, which means is a permanent part of or permanently attached to the lower portions of the legs of a union suit, on the inside of such legs.

As hereinbefore intimated, the term "full-length" as used herein is not intended to exclude union suits or other bifurcated garments having legs which extend only part way down to the ankles, but is intended to include all such garments having legs that extend any distance below the knees, the term merely being employed to distinguish between knee-length garments and garments having longer legs.

I am aware that knee-length undergarments have been provided with hose supporters which extend below the bottoms of the legs of such garments on the outside, and have supporting members extending up the sides of the body of such undergarment, and do not, therefore, seek to cover a combination undergarment and hose supporters of such a character.

What I claim as my invention, and desire to secure by Letters Patent, is—

1. As an improved article of manufacture, a full-length union suit having tabs, with hose-engaging clasps, and buttons attached directly to the lower portions of the legs of said suit on the inside, the tab and button in each case being attached at different points to the leg, in proper spaced relationship to enable the clasp of said tab and said button to co-operate for hose-supporting purposes.

2. As an improved article of manufacture, a full-length union suit having seams on the insides of the legs thereof, and tab, with hose-engaging clasps, and button in each case, said tabs and buttons being attached at different points to one of such legs at the seams, in proper spaced relationship to enable the clasp of said tab and said button to co-operate for hose-supporting purposes.

3. As an improved article of manufacture, a full-length union suit, looped tabs attached above the loops therein to the insides of the legs of such suit, hose-engaging clasps having their top parts passed through the

loops in said tabs, and hose-engaging buttons attached directly to said legs below said tabs.

4. As an improved article of manufacture,
5 a full-length union suit having seams on the insides of the legs thereof, looped tabs attached above the loops therein to the said legs across said seams, hose-engaging clasps

having their top parts passed through the loops in said tabs, and hose-engaging buttons attached to said legs across said seams below said tabs. ¹⁰
